United States Patent Office.

WILLIAM DEERING, OF LOUISVILLE, KENTUCKY.

Letters Patent No. 97,170, dated November 23, 1869.

IMPROVED BALING-PRESS.

The Schedule referred to in these Letters Patent and making part of the same.

Be it known that I, WILLIAM DEERING, of the city of Louisville, State of Kentucky, have invented a new and useful Press for Baling Hay or Cotton, or other materials; and I declare the following specification, with the drawings, forming part thereof, to be a full and complete description of my invention.

Figure 1 represents a front view of the press.

Figure 2, a sectional view of the same, through the plane of its centre.

Figures 3 and 4 show end views of the press.

Figure 5 shows a top view of the press.

Figures 6, 7, and 8 show, on an enlarged scale, parts of fig. 5.

Figure 9 shows a plan view of the eccentric, with its frame.

Similar letters denote the same parts of the apparatus.

My press is of the kind known as the upward-screw press, and is in the usual form of those presses, being placed on an upper floor, and worked by cattle in a room beneath.

Its frame-work is fully shown in the drawings, and therefore requires no specific description.

The frame has a heavy base-block, A, to which it is firmly bolted.

Through the centre of this block is fitted, so that it can be revolved therein, a hollow cylinder or nut, B, having a female-screw thread cut within it.

A male screw, C, is fitted to it, which is, at its top, attached to a platen or block, D, fitted to move up or down within the frame, and having on its upper surface slats *a a*, leaving interstices to permit the passage of the ties used to secure the bales when made up.

To the bottom of B, which extends below the floor, are secured the bars E, for the attachment of animal power; or, if other power be employed, then suitable gearing, instead of the bars, so that by the revolution of B, the screw C, with its platen, can be elevated and depressed.

That part of the frame from *b b* to *c c*, passed over by the platen in its extreme rise and fall, is enclosed with a stout boxing.

Above this, the space *e e* *b b* is closed at the ends, but in front and rear is furnished with strong doors G, the space enclosed between *e e* *c c* being the chamber within which the cotton is packed.

Within the space above this chamber, a piston or plunger, similar to the platen, having slats *f f* on its lower surface, corresponding with *a a*, moves parallel with the platen.

This plunger is connected by a pitman or connecting-rod, J, with a crank or crank-wheel, K, by whose revolution it is moved to or from D.

g g are guide-rods, fixed to the plunger, to steady its passing through cross-bars *i i* of the machine's frame.

The crank-wheel K, placed over the centre of the plunger, is operated by a horizontal cam, L, (see fig. 9,) affixed to the upper part of nut B, near the upper surface of base-block A, or, if desirable, near its under surface.

The cam operates frame M, moving it from one side of the frame to the other.

It is attached, through its arms N, by a hook, j, to the lower limb of a vertical lever, P, which is pivoted, at k, upon an arm, O, projecting from one end of the frame.

The upper end of the lever is connected, by a cord or chain, R, to the wheel K, the cord passing over the periphery of the wheel, so as, with every vibration of the lever, from the frame outward, to give the wheel a semi-revolution, the wheel being brought back to its original position, when the lever moves toward the frame, by a counter-weight, W, also attached to the wheel K, by a cord or chain, S, passing over a pulley, T.

The communication between N and wheel K can be effected by a chain or cord passing around pulleys, as shown by the dotted lines in fig. 1, but a lever is preferable, as shown, for exact action.

A cam and frame are described as the most convenient arrangement for use; but I propose to use any equivalent apparatus, as, for instance, a crank-wheel, driven by a pinion-wheel on the nut B.

The mechanical arrangements to connect the movements of the eccentric with the plunger are not limited to those described, but may be made by other devices familiar to mechanics.

When the plunger is at its highest elevation, it stands, as shown in fig. 1, some distance above the beams U, below which the upper part of the doors G close.

The space between the top of the beam U and the plunger is closed in the rear, but in front is provided with a door, X, hinged on its lower side, and having bent lever-arms r projecting from it, as shown.

This door is automatically opened and shut by an apparatus, on the outer end of the axis or shaft of wheel K; and just outside of the frame of the machine, there is affixed a cam-wheel, Y, (see fig. 5, and diagrams 6, 7, and 8,) shaped as shown.

In front of this wheel, and nearly touching it, pivoted through brackets t t, projecting from the end frame-pieces of the machine is a horizontal roller, Z, carrying at its outer end arms m m.

From the outer ends of these arms, cords or chains V, passing over pulleys p, connect them with the bent arms r, so that the rocking of the roller shall open or close the door X.

The roller Z is operated by a pin, S, projecting from it, which is engaged by the edge of the notch of wheel Y, as shown in figs. 6, 7, and 8, and which, as the

wheel revolves, passes out of the notch, and presses against the outer edge of the wheel, which is so shaped as to hold the pin, with the roller, in the position shown at fig. 8, during the advancing movement of the wheel, and until the reversed motion of the wheel shall drop the pin into the notch, and permit the roller to turn back to its first position.

It will be seen that the first motion of the roller above described shuts the door X, and holds it shut until the return of the pin into the notch, when the door will drop open, and remain open until the wheel, returning to its first movement, brings the pin again against the edge of the notch.

At each end of the frame, reaching from the top of beam U², for some distance above, are two pendent chuck-blocks, Q, whose use will be explained in the description of the working of the machine. They are pivoted, at their top corners, to the frame, and fitted so as to permit them to have a bearing against the frame, capable of resisting a powerful pressure upward.

The method of operating the machine is thus:

The position of the different parts of the machine being, as shown in the drawings, with the doors G closed, the platen D just below the edge of the sill of the doors, and the plunger at its highest elevation, hay, cotton, or other material, is to be filled in at the upper door X, until the chamber between the platen and plunger is full. The machinery is then put in motion by the levers E, moving the platen slowly downward by the screw C, and, by its first semi-revolution, bringing the plunger down to the full extent of its stroke, thereby compressing the mass of material. The next semi-revolution of the screw carries the platen down a short distance, and the plunger up to the top of its stroke. The plunger being operated by the cam L, with its frame M and the lever P², and the cord attaching it to the wheel K, the parts are so arranged, that when it, the plunger, is at its height, the wheel K ceases to move during a portion of the revolution of the screw, allowing time to fill up the space between the plunger and the material on the top of the platen with more material. If more time is needed, the machinery can be stopped a minute. The further revolution of the cam brings the plunger down, condensing the material upon that already on the platen, and thus the operation progresses, with every revolution of the screw, the platen retiring slowly within the packing-chamber, and the plunger making its stroke and return until the material is packed in up to the top of the door. Then the plunger being left standing at the top of the packing-chamber, as shown, the chuck-blocks Q Q are swung inward, so that their

bottoms rest upon the plunger, (see fig. 2,) and brace it firmly down against the frame-pieces U², leaving the slats f f projecting below the beam. The lever P² is then to be detached from the frame M, and the direction of the moving-power reversed, when the platen will be driven upward, and the material further compressed, until the platen shall reach far enough above the sill of the door to permit the bale-ties to be passed between the slats. The compressed material is now properly secured by ties, and the bale is made up. The direction of the power being again changed, the platen is screwed down a trifle, to loosen the bale, which is then removed. Fresh material being again supplied, the chuck-blocks are swung back from their hold, the lever reconnected with M, and the process described repeated on each bale to be made.

During these operations, it is necessary that the door X of the supply-port be closed during the descent of the plunger. This is effected by the movements of the following machinery:

The wheel Y gives a part revolution to the roller Z, as described in the former part of this specification, being driven by wheel K. It is so adjusted, in relation to that wheel and its movements, that it moves the pin S of the roller Z, and, by its arms m m, and cord or chain V, the door X, so as to close it just as the plunger begins its descent, keeps it closed until the plunger has returned to the top of its course, and then lets the door fall open, and continue so, until the plunger begins to move downward. This is done to prevent the loose hay, cotton, and other material, from working out and clogging the plunger, and to keep in the dust which sometimes rises, annoyingly to the workmen.

What I claim as my invention, and desire to secure by Letters Patent, is—

1. The combination of the nut B, screw C, and eccentric L, or its equivalent, when employed with intermediate mechanism, substantially such as is herein described, to give simultaneous movement to the upper and lower platens of a press, substantially in the manner set forth.

2. The combination and arrangement of the eccentric L, frame M, with its arms or guides N, hooks J, and lever P², substantially as and for the purpose described.

3. The combination and arrangement of the cam-wheel Y, roller Z, pulley p, and bent arms r, substantially as shown and described.

WILLIAM DEERING.
